UNITED STATES PATENT OFFICE.

EDWARD HOMMEL, OF SYRACUSE, NEW YORK.

DESIGN FOR A NOSE-PIECE FOR EYEGLASSES.

SPECIFICATION forming part of Design No. 24,434, dated June 25, 1895.

Application filed November 14, 1894. Serial No. 528,818. Term of patent 14 years.

To all whom it may concern.

Be it known that I, EDWARD HOMMEL, a citizen of the United States, residing at Syracuse, in the county of Onondaga and State of New

5 York, have invented and produced a new and original Design for a Nose-Piece for Eye-glasses, of which the following is a specification, reference being had to the accompanying drawings, in which—

10 Figure 1 is an enlarged view of the nose-piece. Fig. 2 is an edge view thereof.

These two views are deemed necessary to fully illustrate my design, the leading feature of which is the nose-piece for eye-glasses com-

15 prising a plain body having edges, the lines of which are concavo-convex in outline, the concavity on one edge merging into a convex-

ity upon the same edge, and the concavity of one edge being opposite to the convexity of the other, such edges being parallel or substantially so, and the ends also. 20

In the drawings —A— is the nose-piece, having in its edges the concavities —a—, and —b—b— are the convexities.

What I claim as my invention, and desire 25 to secure by Letters Patent, is—

The design for a nose-piece for eye-glasses, substantially as shown and described.

In witness whereof I have hereunto set my hand on this 8th day November, 1894.

EDWARD HOMMEL.

In presence of—

JESSIE E. MURRAY,
HOWARD P. DENISON.
